Primary Examiner — Wan Laymon*Assistant Examiner* — Clint A Samuel(74) *Attorney, Agent, or Firm* — Wright Lindsey Jennings LLP; Meredith Lowry(57) **CLAIM**

The ornamental design for a base for a fish habitat, as shown and described.

DESCRIPTION

FIG. 1 is a perspective view of the base for fish habitat;
 FIG. 2 is a top plan view thereof;
 FIG. 3 is a bottom plan view thereof;
 FIG. 4 is a back elevational view thereof;
 FIG. 5 is a front elevational view thereof;
 FIG. 6 is a left side elevational view thereof; and,
 FIG. 7 is a right side elevational view thereof.
 The dashed lines are included for the purpose of illustrating environment only and form no part of the claimed design.
